UNITED STATES PATENT OFFICE.

FRANK S. BALDWIN, OF NEWARK, NEW JERSEY, ASSIGNOR OF ONE-HALF TO
JOHN W. TILLEY, OF CASTLETON, NEW YORK.

ROUNABOUT.

SPECIFICATION forming part of Letters Patent No. 476,597, dated June 7, 1892.

Application filed August 10, 1891. Serial No. 402,291. (No model.)

To all whom it may concern:

Be it known that I, FRANK S. BALDWIN, of Newark, in the county of Essex and State of New Jersey, have invented certain new and useful Improvements in Carrousels; and I do hereby declare the following to be a full, clear, and exact description of the invention, such as will enable others skilled in the art to which it pertains to make and use it, reference being had to the accompanying drawings, which form part of this specification.

My invention relates to an improvement in carrousels; and it consists in certain novel features of construction and in the combination and arrangement of parts, which will be fully described hereinafter, and more particularly referred to in the claims.

The object of my invention is to construct a carrousel which will admit of a rocking or tilting motion while being rotated and which can also be raised from the ground in starting and lowered again in stopping to facilitate the ingress and egress of passengers with safety and dispatch. The weight of the frame, post, and other appliances being counterbalanced, the force required to lift the carrousel is limited to the actual weight of the passengers.

In the accompanying drawings, Figure 1 is a side elevation of my improved carrousel. Fig. 2 is a detail view of the connection between the uprights and frame.

A represents a suitable base, upon which are erected the converging uprights B, upon the upper ends of which is secured the plate D, which is provided with an opening in its center. Extending downward through this opening is the vertically-moving post E, the lower end of which is formed into a screw E'. Supported on the base A and adapted to revolve on the ball-bearing A' is the bevel gear-wheel F, which is provided with a central screw-threaded opening, through which moves vertically the screw E'. This bevel-gear is engaged by the beveled pinion G, secured to the end of the shaft G', which is revolved by the engine shown in Fig. 1.

Journalized in the uprights B are the pulleys B', over which pass the weighted ropes H, the inner ends of which are secured to the collar H', loosely mounted on the post E, but prevented from having any vertical movement

thereon by the stop I. Between this stop and the collar is a ball-bearing I', which prevents any friction between the said parts while the post E is revolving. When it is desired to raise the said post, the gear F is revolved, causing the screw-threaded portion E' to rise through the correspondingly-screw-threaded opening in the gear. This vertical movement is greatly assisted by the upward pull upon the post of the weighted lines.

Secured to the upper end of the post E is a driving-plate J, which is provided with a central socket J' and the peripheral projections K, one edge of each of which is made vertical and the other sloping, as shown at K'. Supported on this plate J is the central tilting frame or casting L, which has a downwardly-extending rounded projection L', which bears in the socket J'. Extending downward from this frame L are the vertical projections M, each of which has a vertical edge and a sloping edge, as shown at M', which engage the sloping edges K' of the projections K for the purpose presently to be stated. The upper side of the frame L is provided with ribs, between which the inner ends of the radiating arms are secured. These arms are inclined downward from a horizontal plane, so as to bring the weight below the point of support, and are braced near their outer ends by the connecting-rods N'.

Extending upward from the plate L is a central post O, which is provided with a plate O' at its upper end, to which the brace-rods P are secured at one end and at their opposite ends to the outer ends of the arms N. Projecting from the plate O' is a swivel P', to which is connected a rope R, by means of which the frame L and the arms N may be tilted and made to revolve at any desired angle from a horizontal plane. This rope may be drawn upon at intervals to give the above result, or its outer end may be secured to a post or other object and the revolving frame held at the desired angle.

Near the outer ends of the arms N are secured the hangers N'', to which are pivoted the seats or other carriers S. The forward-and-backward movement of these carriers is limited by the coiled springs T, which are connected to the opposite ends of the pivoted bars T' on the under sides of the carriers. By

this means a continuous connection is made between the carriers, thus giving them a uniform movement or swing. The springs T are sufficiently elastic to allow the carriers to 5 yield to the natural centrifugal force while being rotated, thus avoiding the danger of persons being thrown out.

In operation, the carriers resting upon the ground, the passengers take their seats and 10 the wheel F is caused to revolve, while the post and frame are checked from turning. This operation causes the post and frame to rise by the action of the screw until the stop at the bottom of the post comes in contact 15 with the bottom of the wheel F, when the post and wheel will revolve in unison. The projections on the driving-plate J on the top of the post coming in contact with those of the tilting plate L the said plate and the arms N 20 are caused to revolve, which action can be maintained as long as desired, the rocking motion being controlled by means of the rope R, as before described. The rocking action of the frame is limited by the length of the 25 lugs on the driving-plate, thus preventing the carriers from striking the ground while in motion.

When it is desired to stop the revolution of the frame, the motion of the wheel F is arrested. The momentum of the frame causes 30 the sloping edges of the projecting lugs on the tilting plate to come in contact with those of the driving-plate, thus causing the post to continue revolving, and by means of the screw 35 the frame and the carriers are steadily lowered until the latter reach the ground. It is obvious that the lowering of the screw can be accelerated by causing the wheel F to revolve in the opposite direction from that of 40 the screw. As the beveled edges engage, as above described, any oscillation which the frame might otherwise have is prevented.

Having thus described my invention, I claim—

45 1. In a carrousel, a base, a wheel journaled thereon provided with a screw-threaded opening, means for revolving the wheel, uprights supporting a guiding-plate, a vertically-moving screw-threaded shaft, a collar loosely 50 mounted on the shaft, weighted ropes connected at their inner ends to the collar and passing over pulleys in the said uprights, and a frame supported on the said shaft, the parts being combined to operate substantially as 55 shown and described.

60 2. In a carrousel, a vertical shaft, means for revolving the shaft, a frame J, supported on said shaft and having peripheral projections and a central socket, and an arm-carrying 65 frame L, having a depending bearing which fits the said socket and depending projections which engage the projections K, the parts being combined to operate substantially as shown and described.

65 3. In a carrousel, a vertical shaft, means for revolving the shaft, a frame supported there-

on having a socket and peripheral projections, one edge of each of the latter being made vertical and the other edge made sloping, and a frame having a depending projection which bears in the said socket and which is also provided with downward projections which have vertical and sloping edges which engage the corresponding edges on the projections K, the parts being combined to operate substantially as shown and described.

4. In a carrousel, a vertical shaft, means for revolving the shaft, a frame supported on the upper end of the shaft, arms extending outward from the frame, carriers pivotally connected to the said arms, bars pivoted to the carriers, and springs connecting the bars, the parts being combined to operate substantially as shown and described.

5. In a carrousel, a vertical shaft, means for revolving the shaft, a frame supported on the upper end of the shaft, arms extending outward from the frame, carriers pivotally connected to the said arms, and springs connecting the carriers, the parts being combined to operate substantially as shown and described.

6. In a carrousel, a base, a wheel mounted thereon provided with a screw-threaded opening, uprights supporting a guiding-plate, a screw-threaded shaft, a stop secured to the 95 shaft, a collar loosely mounted on the said shaft, a ball-bearing interposed between the stop and the collar, weighted ropes connected to the collar and adapted to pass over pulleys in the said uprights, and a frame supported 100 on the upper end of the shaft, the parts being combined to operate substantially as shown and described.

7. In a carrousel, a frame, a post, and a means for moving the post vertically in the frame, a 105 collar loosely secured to said post, and weighted ropes adapted to pass over rollers journaled in the frame and which are connected to said collar at their inner ends, substantially as shown and described.

8. In a carrousel, a vertical shaft and a means for revolving the same, combined with a frame pivotally supported on the upper end of the shaft, a rod extending upward from the center of the frame, and a rope connected to the 115 said rod, whereby the frame is oscillated, substantially as shown and described.

9. In a carrousel, a vertical shaft and a means for revolving the same, combined with a plate pivotally supported on the upper end of the 120 shaft, projecting ribs on the upper face of the plate, arms secured to the said plate between the said ribs and radiating outward therefrom, and carriers supported by the said arms, substantially as shown and described.

In testimony whereof I affix my signature in presence of two witnesses.

FRANK S. BALDWIN.
